UNITED STATES PATENT OFFICE.

BERNARD R. PFEIFER, OF JESSIE, NORTH DAKOTA, ASSIGNOR TO THE PFEIFER STRAW GAS PRODUCER COMPANY, OF FARGO, NORTH DAKOTA, A CORPORATION OF NORTH DAKOTA.

GAS-GENERATING-RETORT CONSTRUCTION.

1,364,801.

Specification of Letters Patent.

Patented Jan. 4, 1921.

Application filed August 26, 1919. Serial No. 319,916.

To all whom it may concern:

Be it known that I, BERNARD R. PFEIFER, a citizen of the United States, residing at Jessie, in the county of Griggs and State of North Dakota, have invented new and useful Improvements in Gas-Generating - Retort Construction, of which the following is a specification.

The primary object of this invention is the production of gas, creosote, tar and other products from straw and other vegetation in a simple and inexpensive manner, and by which the material from which the gas and other products are produced, can be handled expeditiously and economically.

The accompanying drawing forming part of this specification, is a vertical longitudinal section of a device by which my improvement can be carried into use.

In the drawing a furnace is shown having a front 2, a back 3, a grate 4 and an upwardly and backwardly slanting wall 5. Placed above the grate is a retort having a floor 7, a back 8 and a top wall 12, the front 25 of said retort being provided with a door 11 closing an entrance through which straw or other material to be treated can be passed into the retort chamber. The top of the retort chamber has a gas duct 14 for the egress of gas generated from the straw and other material which is treated in the retort. The retort chamber is provided with a plurality of flues 13, the front ends of which are connected with a smoke chimney 15. The back ends of said flues connect with the fire chamber below the retort, a passage 9 being provided between the wall 8 of the retort and the back 3 of the structure.

In operation the material to be treated is packed around the flues and the door 11 sealed shut. Heat from the fire on the grate 4 passing through and radiating from the flues serves to carbonize and reduce the material in the retort into its constituent parts; namely, gas, creosote, tar and other products, the gas passing upwardly and out through the duct 14. The creosote, tar and remaining products can from time to time

be removed from the retort through the retort doorway by removing the door 11.

By the use of my invention the straw and other products placed in the retort can be efficiently and quickly reduced to gas, creosote and other constituents by inexperienced operators and the gas and residue collected.

In accordance with the patent statutes, I have described the principles of operation of my invention, together with the apparatus which I consider to represent the best embodiment thereof but I desire to have it understood the construction shown is only illustrative and that the invention can be carried out by other means and applied to uses other than those above set forth, within the scope of the following claims.

Having described my invention what I claim as new and desire to secure by Letters Patent is:

1. In an apparatus for producing gas and other products from vegetable material, comprising in combination, a furnace housing forming a combustion chamber, a retort within said housing and extending for a distance of its length above said combustion chamber, said retort having a vent duct forming an outlet therefrom, a plurality of horizontal flues traversing the upper portion only of said retort and opening into the housing for communication with said combustion chamber, the retort being provided with an opening at one end below the flues for access to permit material to be freely introduced and removed from said retort, and a smoke outlet duct connected with said flues remote from their communication with the housing and exteriorly of the latter.

2. In an apparatus for producing gas and other products from vegetable material, comprising in combination, a furnace housing forming a combustion chamber, a retort within said housing and extending for a distance of its length above said combustion chamber, said retort having a vent duct at one end and forming an outlet therefrom, a plurality of horizontal flues traversing the

upper portion only of said retort and opening into the rear of said housing and directly communicating with the combustion chamber, the retort being provided at one end below the flues for access to permit material to be freely introduced and removed from said retort, and an enlarged smoke outlet duct communicating with said flues

exteriorly of the housing and draft regulating means in said last mentioned outlet to control the rapidity of combustion.

Signed at Jessie, in the county of Griggs and State of North Dakota, this 30th day of July, 1919.

BERNARD R. PFEIFER.
